GLAZING TOOL

Lewis B. Ives, Hollywood, Calif., assignor to Northrop
Architectural Systems, Los Angeles, Calif., a corpora-
tion of California

Filed Apr. 2, 1964, Ser. No. 79,317

Term of patent 14 years

(Cl. D54—13)

FIGURE 1 is an edge view of a glazing tool, showing my new design.

FIGURE 2 is a side view as seen from the right of FIGURE 1.

FIGURE 3 is a view as seen from above FIGURE 2.

FIGURE 4 is a view as seen from below FIGURE 2.

FIGURE 5 is a view of the reverse side of FIGURE 2.

FIGURE 6 is a cross-section view taken along 6—6 of FIGURE 5.

FIGURE 7 is a cross-section view taken along 7—7 of FIGURE 5.

FIGURE 8 is a cross-section view taken along 8—8 of FIGURE 5.

FIGURE 9 is a cross-section view taken along 9—9 of FIGURE 5.

FIGURE 10 is a cross-section view taken along 10—10 of FIGURE 5.

I claim:

The ornamental design for a glazing tool, substantially as shown.
